COVER UNIT FOR ASH RECEIVERS

Howard F. Reichenbach, Waterbury, Conn., assignor to Chase Brass & Copper Co. Incorporated, Waterbury, Conn., a corporation

Application May 9, 1938, Serial No. 206,705

3 Claims. (Cl. 131—51)

This invention relates to an improved cover-unit and more particularly concerns an improved cover-unit for a receptacle for receiving cigar and cigarette stubs, ashes, etc.

- 5 One of the objects of the present invention is to provide an arrangement whereby all of the surfaces of a cover-unit are made easily accessible and can be readily cleansed and maintained bright and free of tarnish or odor.
- 10 Another object of this invention is to provide a cover-unit for an ash-receiver of the class described of such construction as to facilitate access to the interior of the receiver for discharge of the contents of the receiver and for cleaning 15 its interior.

20 A further object of the invention is the provision of simple mounting-means for a tiltable closure of the cover-unit whereby it can be quickly removed for access to the interior of an ash-receiver and for cleaning the said closure, as well as the interior surfaces of its supporting-member.

25 It is also the object of this invention to provide a cover-unit, as described, in which centrally-arranged means are provided on the tiltable closure of the cover-unit, whereby cigars or cigarettes can be rested on the receiver without unburned portions of these articles coming in contact with ashes or the like deposited on the tiltable member of the cover-unit.

30 With the above and other objects in view, as will appear to those skilled in the art from the present disclosure, this invention includes all features in the said disclosure which are novel over the prior art.

35 In the accompanying drawing, in which certain modes of carrying out the present invention are shown for illustrative purposes:

40 Fig. 1 is a perspective view showing the cover-unit in place on an ash-receiver of the table type, which is represented by broken lines of the cover-unit taken on the line 2—2 of Fig. 1;

45 Fig. 2 is a transverse sectional view of the cover-unit taken on the line 2—2 of Fig. 1;

50 Fig. 3 is a fragmentary sectional view on the line 3—3 of Fig. 1;

Fig. 4 is a similar view taken on the line 4—4 of Fig. 3;

55 Fig. 5 is a perspective view of the rim-ring; and

Fig. 6 is a plan view of the tiltable closure.

In the form illustrated, the cover-unit is shown applied to a bowl B of an ash-receiver of the table type, which is represented by broken lines in Fig. 1, but it will be understood that the cover-

unit of this invention can be equally well applied to the bowl of an ash-receiver if the pedestal type.

The cover-unit includes a rim-ring, generally designated by the reference character 10 and a receiving-disk or closure 11 which is tiltably and removably mounted in and normally closes an opening 15 within the said rim-ring. 5

The rim-ring 10, which is preferably drawn from sheet-metal, includes an upper face-portion 12, the outer portion of which is formed to provide a rim-seat 12^a for engaging the rim of bowl B. At the outer edge of the rim-seat 12^a, there is formed a depending skirt 13, which overlaps the outer surface of the wall of the bowl B adjacent the rim thereof. From the inner edge of the rim-seat 12^a, the face-portion 12 slopes downwardly and inwardly, as indicated at 12^b, and at the inner edge of the face-portion 12 an interior downwardly-extending annular flange 14 is formed, which defines the opening 15 within the rim-ring 10. 10 15 20

The opening 15 in the rim-ring 10 is normally closed by the receiving-disk 11, and novel mounting-means are provided for tiltably and removably mounting the said receiving-disk 11 in the said opening 15 of the rim-ring 10. 25

In accordance with the invention, the rim-ring 10 is provided with sockets for receiving trunnions or pintles of the receiving-disk 11, and at least one of the said sockets is provided with a lead-passage dimensioned to enable one of the trunnions or pintles to be passed therethrough. 30

As shown in the drawing, there is provided in the interior annular flange 14, diametrically-opposite retaining-sockets or bearing-openings 16—16, which are preferably of rectangular shape. In the preferred embodiment of the invention, two lead-passages 17—17 are also provided, one extending from each of the retaining-sockets 16 outwardly through part of the sloping portion 12^b of the face-portion 12 of the rim-ring. The lead-passages 17—17 and the retaining-sockets 16—16 are arranged to receive pintles or trunnions 18—18 formed integral with and at diametrically-opposite portions of the receiving-disk 11. These pintles or trunnions 18 are, like the retaining-sockets 16, of rectangular shape, but are markedly greater in width than in thickness. 35 40 45 50

The retaining-sockets 16 are of such width as to provide seats 19—19 for engagement by the bottom faces 20—20 of the trunnions 18—18, and the height of the said retaining-sockets 16—16 is of such extent as to permit turning movements 55

of the said trunnions 18-18 within the said retaining-sockets. In this manner, the receiving-disk 11 is normally held by gravity in position to close the opening 15 in the rim-ring 10 and to receive cigar and cigarette ends and ashes, and may be tilted when desired to empty ashes or the like deposited on the said receiving-disk, into the bowl B.

As is shown, the sockets 16-16 are enlarged with respect to the lead-passages 17-17, which, as stated, extend outwardly from the top thereof. The top walls 21-21 respectively of the retaining-sockets 16-16 extend at opposite sides of the junction of each lead-passage 17 with its retaining-socket 16. The top walls 21-21 thus provide retaining-walls for normally holding the trunnions 18-18 in place within the retaining-sockets 16-16 and prevent the receiving-disk 11 from falling out should the ash-receptacle be accidentally upset. To further guard against the receiving-disk 11 becoming displaced with respect to the rim-ring 10, the distance between the extreme outer edges of the diametrically-opposite trunnions 18-18 slightly exceeds the distance between the outer ends of the lead-passages 17-17, so as to prevent the displacement of the receiving-disk 11 should, by any chance, the side-edges 22-22 of the said trunnions 18-18 register with the lead-passages 17-17 by the accidental upsetting of the ash-receptacle.

The width of the lead-passages 17-17, while considerably less than the width of the retaining-sockets 16-16, is slightly greater than the thickness of the trunnions 18-18. When the receiving-disk 11 is tilted to a vertical position and one of the side-edges 22-22 of the trunnions 18-18 thereof brought into registry with their respective lead-passages 17-17, one of the said trunnions may be passed upwardly from its retaining-socket 16 and through the lead-passage 17 leading therefrom. With a given trunnion 18 passed upwardly through the adjacent lead-passage 17, as just described, the diametrically-opposite trunnion 18 may also be passed upwardly through the lead-passage 17 leading outwardly from the adjacent retaining-socket 16, or if it is desired, the said trunnion 18 may be passed radially out of the said adjacent retaining-socket 16, to thus remove the receiving-disk 11 from the rim-ring 10. To insert the receiver-disk 11 in place for closing the opening 15 in the rim-ring 10, the procedure above set forth is reversed, that is, a given one of the trunnions 18 is either passed edge-first through one of the lead-passages 17 into a retaining-socket 16 or directly into the said retaining-socket, which permits the diametrically-opposite trunnion 18 to be passed through the lead-passage 17 into the adjacent retaining-socket 16.

In accordance with the invention, the sanitary nature of the device is further promoted by providing means carried by the said receiving-disk for supporting cigars and cigarettes substantially or entirely out of contact with the said receiving-disk. These means comprise a separate rest-block, generally designated by the reference character 25, which may be suitably secured to the central portion of the receiving-disk 11 as by means of a screw passed upwardly through the said receiving-disk and into the said rest-block.

The rest-block 25 which is composed of suitable heat or fire-resistant material such as Bakelite, glass or the like, may be of any desirable shape and is provided with vertically-extending flutes, grooves or channels for receiving the lighted ends 75 of cigars or cigarettes. The said rest-block is

also provided with holding-edges which slope upwardly from its central portion for holding a cigar or cigarette against rolling and entirely out of contact with the receiving-disk 11. In the example illustrating this arrangement, the rest-block 25 is star-shaped and is provided between its points 26 with vertically-extending wedge-like grooves 27. When a cigar or cigarette is placed with its lighted end in one of said grooves 27, the opposite portion will rest on the face-portion 10-12 of the rim-ring 10, and the intermediate unburned portion of the cigar or cigarette will be held substantially out of contact with the receiving-disk 11 and any ash that may lie thereon. As shown, the rest-block 25 is formed with a central depression 28, and the top edges 29 of the star-shaped rest-block extend radially and upwardly from the said central depression. By this arrangement, a cigar or cigarette may be placed on the top of the rest-block 25 and supported on high portions of adjacent top-edges 29, wholly out of contact with the receiving-disk 11 and any ash that may be deposited thereon, and be held in such manner that the cigar or cigarette will not roll from said rest-block 25 onto the receiving-disk 11.

From the foregoing, the advantages of the described arrangement will be clear, and it is apparent that a cover-unit constructed and arranged in accordance with the described invention will provide means whereby the desirable objects set out in the fore part of the present disclosure, are fully attained.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalence range of the appended claims are intended to be embraced therein.

I claim:

1. A cover-unit for an ash-receiver of the class described, including a rim-ring having a face-portion and an interior downwardly-extending annular flange; a receiving-dish for closing an opening within said rim-ring; and mounting-means for said receiving-dish comprising diametrically - opposite, laterally - extending, flat hinge-ears integral with said receiving-dish, diametrically-opposite, rectangularly-shaped retaining-sockets formed in said interior flange, and a lead passage formed in the face-portion of said rim-ring and leading into one of said retaining-sockets, the said retaining-sockets being enlarged with respect to said lead-passage and dimensioned for seating of the bottom faces of said hinge-ears and for turning movements of said hinge-ears therein, and the width of said lead-passage being greater than the thickness of either of said hinge-ears for the reception of an end-face of a flat hinge-ear and passage of the said hinge-ear therethrough, whereby said receiving-dish is tiltably and removably positioned in the opening within said rim-ring.

2. A cover-unit for an ash-receiver of the class described including a rim-ring having a face-portion and an interior downwardly-extending annular flange; a receiving-dish for closing an opening within said rim-ring; and mounting-means for said receiving-dish comprising diametrically - opposite laterally - extending flat hinge-ears integral with said receiving-dish, diametrically-opposite rectangularly-shaped retain-

- ing-sockets formed in the said interior flange, and a lead-passage formed in the upper face-portion of said rim-ring and leading into each of said retaining-sockets, said retaining-sockets being 5 enlarged with respect to said lead-passages and dimensioned for the seating of the bottom faces of said hinge-ears and for turning movements of said hinge-ears therein, and the width of each of said lead-passages being greater than the 10 thickness of said hinge-ears for the reception of an end-face of one of said hinge-ears and the passage of the said hinge-ear therethrough, whereby the said receiving-dish is tiltably and removably positioned in the opening within said 15 rim-ring.
3. A cover-unit for an ash-receiver of the class described including a rim-ring having a face-portion and an interior downwardly-extending annular flange; a receiving-dish for closing an opening within said rim-ring; and mounting-means for said receiving-dish comprising diametrically - opposite laterally - extending flat hinge-ears integral with said receiving-dish, dia- 20 metrically-opposite rectangularly-shaped retaining-sockets formed in said interior flange, and a lead-passage formed in the upper face-portion of said rim-ring and leading into each of said retaining-sockets, each of said flat hinge-ears 5 being of substantially greater length and breadth than thickness, and each of said retaining-sockets being enlarged with respect to said lead-passages, the width of each of said retaining-sockets accomodating and providing a seat for the bottom 10 face of one of said hinge-ears, and the height of each of said retaining-sockets being such as to allow for turning movement of the hinge-ear therein, and the width of each of said lead-passages being less than the length and breadth of 15 the hinge-ears and being greater than the thickness of the said hinge-ears for the reception of an end-face of one of said hinge-ears and the passage of the hinge-ear therethrough, whereby the said receiving-dish is tiltably and removably 20 positioned in the opening within said rim-ring.

HOWARD F. REICHENBACH.
